UNITED STATES PATENT OFFICE.

HENRY H. VAUGHAN, OF CLEVELAND, OHIO, ASSIGNOR TO THE RAIL-ROAD SUPPLY COMPANY, OF CHICAGO, ILLINOIS, A CORPORATION OF ILLINOIS.

MACHINE FOR MANUFACTURING CHANNEL-PINS.

No. 821,556.

Specification of Letters Patent.

Patented May 22, 1906.

Application filed June 21, 1902. Serial No. 112,683.

To all whom it may concern:

Be it known that I, HENRY H. VAUGHAN, a citizen of the United States, residing at Cleveland, county of Cuyahoga, State of Ohio, have invented a certain new and useful Improvement in Machines for Manufacturing Channel-Pins; and I declare the following to be a full, clear, and exact description of the same, such as will enable others skilled in the art to which it pertains to make and use the same, reference being had to the accompanying drawings, which form a part of this specification.

My invention relates generally to a machine for making tapered pins, and more particularly to manufacturing channel-pins for electrically connecting the ends of wire bonds to adjoining railroad-rails.

In connecting small electrical conductors to relatively large conductors it is customary to retain the ends of the small conductor in holes formed in the large conductor by means of wedge-shaped pins. In the art of railroad signaling, for instance, the adjoining ends of rails are electrically connected by wire bonds, between the ends of which and the rails are interposed channel-pins. It is customary to provide holes through the webs or bases of the rails, in which the ends of the wire bonds are secured. Preferably tapered channel-pins are employed which partially surround the ends of the bonds and which when driven in the holes in the rails securely unite the bonds to the rails and form electrical connections of the requisite capacity. It is essential that the pins should be tapered, so as to be driven readily into the holes in the rails, and at the same time be of such cross-section that when driven into the rails they will be folded closely around and tightly engage the ends of the bonds.

The object of my invention is to provide a machine for tapering the end of a rod having the desired cross-section and shearing off a portion of the rod the predetermined length of the pin.

A further object of my invention is to provide a machine for quickly and economically manufacturing tapered pins which will be simple in construction and efficient in operation.

My invention, generally described, consists

in a vertically-movable die coöperating with a fixed die to bevel upwardly the under surface of the end of the rod, a pair of horizontally-movable dies to taper the exterior surface of the end of the rod, and a shearing knife for cutting off a portion of the rod the predetermined length of the pin.

My invention will be more fully described hereinafter with reference to the accompanying drawings, in which the same is illustrated as embodied in a convenient and practical form, and in which—

Figure 1 is a front elevation view of my improved machine; Fig. 2, a front elevation view of the frame separate from the parts supported thereby; Fig. 3, a central sectional view taken on line 3 3, Fig. 1, looking in the direction of the arrows; Fig. 4, an enlarged sectional view through one of the cross-heads for supporting one of the horizontally-movable dies; Fig. 5, an enlarged elevational view of the dies; Fig. 6, a side elevational view of the vertically-movable die and one of the horizontally-movable dies, and Fig. 7 a plan view of the horizontally-movable dies and the stationary die.

Similar reference characters are used to designate similar parts in the several figures of the drawings.

Reference character A indicates the supporting-frame of the machine, which may be conveniently supported upon pairs of legs B' and B''. Each pair of legs, as shown in Fig. 3, is bolted to the under side of the frame A and also to the floor. The frame A is provided with bearings A' A'', in which is journaled a power-shaft C'. The portions A^o of the bearings beneath the shaft C' are preferably adjustable upon the frame A by means of set-screws a^o, as clearly shown in Fig. 3. Bushings a' preferably surround the shaft C' between the same and the bearings. One end of the shaft C' is provided with means for communicating power thereto—as, for instance, a belt-pulley D. A gear-wheel D' is fixed upon the shaft C' adjacent to the belt-pulley D. The end of the shaft C opposite the belt-pulley is provided with a crank c', which is surrounded by a strap secured to the upper end of a connecting-rod e'. The lower end of the connecting-rod e' is pivotally secured to a cross-head E'. The cross

- head E' engages guides E⁵, adjustably supported upon the frame A. The guides E⁵ are provided with openings loosely surrounding pins e, secured in openings a¹⁰ in the parallel flanges A⁵ A⁵, projecting from the front of the frame A, as shown in Fig. 2. The parallel flanges A⁵ A⁵ are provided with lugs a⁵ a⁵, extending beyond the surfaces thereof. Set-screws e⁵ e⁵ are supported in the lugs a⁵ a⁵ and bear against the guides E⁵ E⁵, thereby adjusting the positions of the latter, such adjustment being permitted by the play between the pins e e and the surrounding holes in the guides.
- 15 Two shafts C² and C³ parallel to the shaft C' are journaled in the opposite sides of the frame A in a horizontal plane below the plane of the shaft C'. Bearings similar to those provided for the shaft C' are also provided
- 20 for the shafts C² and C³. Secured to the ends of the shafts C² and C³ are gear-wheels D² and D³, which mesh with the gear-wheel D' on the shaft C'. The ends of the shafts C² and C³ opposite the gear-wheels are provided
- 25 with cranks c² and c³, respectively. These cranks are surrounded by straps secured to the ends of connecting-rods e² and e³. The opposite ends of the connecting-rods e² and e³ are pivotally secured to cross-heads E² and E³.
- 30 The cross-heads are supported by guides similar to the guides above described in connection with the cross-head E'. The parallel guides E⁶ E⁶ are supported upon the frame A by means of pins e, fixed in openings a¹⁰ in parallel flanges A⁶ A⁶, formed on the frame A. The parallel flanges are provided with outwardly-projecting lugs a⁶, in which are located set-screws e⁶ e⁶, which engage the guides E⁶ E⁶ to adjust the latter with respect
- 35 to the cross-head E². Guides E⁷ E⁷ are secured to the parallel flanges A⁷ A⁷ of the frame A by means of pins e, loosely located in openings in the guides. The parallel flanges A⁷ are provided with lugs a⁷, in which
- 40 are located set-screws e⁷, which engage and adjust the guides E⁷ relative to the cross-head E³. The connecting-rods e', e², and e³ are preferably adjustable in length by means of turnbuckles in a well-known manner. Bushings c are preferably interposed between the straps on the ends of the connecting-rods and the respective cranks.
- 45 The inner ends of the cross-heads E² and E³ support castings F² and F³, in which are mounted dies f² and f³. Set-screws f⁵ are provided for securing the dies within the recesses in the castings, as clearly shown in the drawings. The castings may be conveniently secured to the ends of the cross-heads
- 50 by means of screws F. The vertical faces of the dies f² and f³ are provided with recesses corresponding in shape to the desired contour of the pin which is to be manufactured.
- 55 The lower face of the cross-head E' supports a casting F' by means of screws F pass-

ing through flanges on the casting and into the end of the cross-head. A vertical passage is formed at the center of the lower portion of the casting F', as shown in Fig. 5, in which are inserted a die f' and a shearing-knife g'. The shearing-knife extends below the lower surface of the die f', as clearly shown in Fig. 6. Keeper-bars G and G² are secured to the front and back faces of the lower portion of the casting F' by means of screws g. A set-screw f extends through the keeper-plate G and engages the front surface of the knife g' and retains the latter in the casting F' and also retains the die f' between the back vertical surface of the knife and the front surface of the keeper G².

To the front face of the projecting portion A⁴, formed on the frame A, is secured a casting F⁴, provided with a vertical dovetail channel. Located within the dovetail channel is a die f⁴. A groove f⁶ extends along the upper surface of the die f⁴, the casting F⁴, and the adjacent portion A⁴ of the frame. A keeper a⁴ is secured above the portion A⁴ of the frame and is provided with a groove in its under surface registering with the groove f⁶. The portion of the groove f⁶ formed in the die f⁴ is inclined upwardly, as indicated in Fig. 6.

A bracket H, substantially of an inverted-V shape, is secured to the portion A⁸ of the frame by means of bolts H' passing through the lower ends of the bracket and into the portion A⁸ of the frame. Collars or spools a⁸ surround the bolts H' between the brackets H and the front surface of the frame, thereby spacing the bracket the desired distance in front of the frame. At the top of the bracket H is provided an opening, through which passes a screw-threaded stop h, which may be adjusted in the bracket and locked at the desired position by means of nuts h', as is shown in Figs. 6 and 7.

The operation of my improved machine is as follows: The rod which is to be used in manufacturing the pins, which may be of U-shaped cross-section when channel-pins are to be made, is inserted in the groove f⁶, so that the end of the rod is flush with the outer vertical face of the stationary die f⁴. The rotation of the shaft C' by means of power applied to the belt-pulley D reciprocates the cross-head through the interposed connecting-rod e' and crank c'. The downward movement of the cross-head E' carries the die f' into engagement with the portion of the rod immediately above the stationary die f⁴ and casting F⁴. The inclination of the groove f⁶ in the die causes the under surface of the end of the rod to be beveled upwardly when subjected to compression between the movable die f' and the co-operating fixed die. The rod is then slid through the groove f⁶ until it engages the inner end of the adjustable stop h'. The rotation of the shafts

C² and C³ through the engagement of the gear-wheels D² and D³ with the gear D' reciprocates the cross-heads E² and E³ toward and away from each other. The movement 5 of the cross-heads toward the center brings the dies f² and f³ into proximity to each other. The recesses formed in the faces of the dies surround the projecting portion of the rod and compress the same, thereby im- 10 parting thereto a contour corresponding to the shape of the recesses in the dies. The continued rotation of the shafts C² and C³ one hundred and eighty degrees moves the dies away from each other and permits the 15 shearing-knife g' to pass downwardly adjacent to the vertical face of the stationary die f⁴, thereby shearing off the portion of the rod projecting beyond the front edge of the stationary die. The continued downward movement of the cross-head E' causes the die 20 f' to engage the end of the rod adjacent to the severed portion and impart thereto an upward bevel through the compression exerted by the die f' and the stationary die 25 f⁴. The rod is again slid through the groove f⁶ into contact with the stop h', and the continued rotation of the several shafts elevates the cross-head E', and with it the die f' and shearing-knife g', out of the path of movement 30 of the horizontal dies f² and f³, which then engage and compress the projecting portion of the rod. The length of the pin may be regulated by adjusting the stop h' within the bracket H.

35 The relation between the cranks c', c², and c³ is such that the machine may operate continuously without any interference between the horizontally-movable dies and the vertically-movable die and shearing-knife. It 40 is only necessary that the rod should be fed through the groove f⁶ each time a section is sheared off in order that the machine may make pins without intermission.

From the foregoing description it will be 45 observed that I have invented an improved machine for manufacturing tapered pins, more especially channel-pins, by subjecting the end of the rod to compression first in one direction and subsequently in a different 50 direction and then shearing off a portion of the rod the desired length of the pin.

While I have described more or less precisely the details of construction, I do not 55 wish to be understood as limiting myself thereto, as I contemplate changes in form, the proportion of parts, and the substitution of equivalents as circumstances may suggest or render expedient without departing from the spirit of my invention.

60 Having now fully described my invention,

what I claim as new, and desire to secure by Letters Patent, is—

1. In a machine of the character described, the combination with a pair of coöperating relatively movable dies, a stationary die, a 65 third movable die coöperating with the stationary die, a shearing-knife coöperating with said stationary die, and means for operating said movable dies and said knife whereby said pair of movable dies are 70 moved apart and coincidentally said third movable die and said shearing-knife are moved toward said stationary die.

2. In a machine of the character described, the combination with a pair of reciprocating 75 coöperating dies, a stationary die located in a plane out of but adjacent to the path of movement of said pair of dies, a third reciprocating die the path of movement of which is in alinement with said stationary die, a 80 shearing-knife coöperating with said stationary die and movable in a path intercepting the path of movement of said pair of dies, and means for operating said reciprocating dies and said knife. 85

3. In a machine of the character described, the combination with a supporting-frame, of a pair of coöperating relatively movable dies guided on said frame, an upwardly-inclined stationary die mounted upon said 90 frame and located out of the plane of movement of said pair of dies, a third movable die coöperating with said stationary die and guided upon said frame, a shearing-knife movable with said last-mentioned die and 95 having a path of movement adjacent to said stationary die, and means for operating said movable dies and said knife.

4. In a machine of the character described, the combination with a frame, of a plurality 100 of rotatable shafts journaled in said frame, cranks on the corresponding ends of said shafts, meshed gear-wheels secured to the opposite ends of said shafts, cross-heads operatively connected to said cranks, guides 105 for said cross-heads adjustably secured to said frame, a pair of coöperating dies secured to a pair of said cross-heads, an upwardly-inclined stationary die mounted upon said frame, a third movable die coöperating 110 with said stationary die and secured to another of said cross-heads, and a belt-pulley secured to one of said shafts for rotating the same.

In testimony whereof I sign this specification in the presence of two witnesses.

HENRY H. VAUGHAN.
